United States Patent Office.

SAMUEL JONES ANDERSON, OF CAZENOVIA, NEW YORK.

Letters Patent No. 100,837, dated March 15, 1870.

IMPROVED RAILWAY-CAR COUPLING.

The Schedule referred to in these Letters Patent and making part of the same

To all whom it may concern:

Be it known that I, SAMUEL JONES ANDERSON, of Cazenovia, in the county of Madison, and State of New York, have invented a new and useful Improvement in Car-Coupling; and I do hereby declare that the following is a full, clear, and exact description thereof, which will enable others skilled in the art to make and use the same, reference being had to the accompanying drawings forming part of this specification, in which—

Figure 1 is a vertical longitudinal section of my improved car-coupling, taken through the line x x , fig. 2.

Figure 2 is a top view of the same.

Similar letters of reference indicate corresponding parts.

My invention has for its object to furnish an improved car-coupling, which shall couple the cars by means of the ordinary coupling-pin, which shall be self-coupling, and which will uncouple itself, should one or more of the cars run or be thrown from the track, and which shall at the same time be simple in construction and reliable in use; and

It consists in the construction and combination of various parts of the coupling, as hereinafter more fully described.

A is the bumper-head, which is made broader and of about the same depth as the ordinary bumper-head. The mouth of the bumper-head is beveled off or made hopper-shaped, in the ordinary manner, to guide the coupling-link into place when the cars are run together.

B is the coupling-pin, which is made long, and which passes down through a tubular guide, C, attached to the upper part of the bumper-head A, to keep the pin B always in a vertical position.

D is a plate sliding in grooves upon the under side of the top part of the bumper-head A, and which is moved back and forward by a pin or arm, E, attached to its rear end, and projecting through a slot in the top part of the bumper A, as shown in figs. 1 and 2.

The plate D is designed to be moved forward when the coupling-pin B is withdrawn, to support the said pin ready to drop through the link, when the cars are run together.

The rear end of the plate D is bent downward, or has a downwardly-projecting flange, F, formed upon it, against which the entering link strikes when the cars are run together, pushing the plate D, and allowing the pin B to drop through the link, coupling the cars.

When it is desired to have the cars run together without being coupled, the plate G, that slides in the same grooves as the plate D, and in front of the said plate D, is pushed back, so that the pin B may rest upon it, as shown in fig. 1.

H is a tubular guard surrounding the tubular guard C, and the lower end of which is secured to the upper part of the bumper A.

I is a coiled spring placed in the space between the tubes C and H, and the lower end of which is secured in the lower part of the said space.

The spring I, when compressed into the space between the tubes C and H, is secured in place by the catches J, the hooked upper ends of which rest upon the upper ends of the spring I, so as to hold it.

The lower parts of the catches J rest upon and are secured to the upper part of the bumper A, by bolts which pass through slots in the said bumper.

The catches J are also connected with the levers K by bolts which pass through slots in the upper part of the said bumper A.

The levers K extend along the sides of the cavity of the bumper A in such positions that the coupling-link will not touch the said levers while the cars are upon the track, even when going around the shortest curves.

The inner ends of the levers K are pivoted to the bumper-head A, and their outer ends have guide-plates K' attached to them, which project through holes in the sides of the bumper, the design of said plates being to protect the ends of the levers, and guard against the possibility of the end of the entering link injuring the said levers or entering behind them.

The levers K are connected to each other and made to move together by the connecting-bars L and lever M.

The outer ends of the bars L are connected to the levers K by bolts passing through slots in the lower part of the bumper, and their inner ends are pivoted to the ends of the equal-armed lever M, which is pivoted at its central point to the lower part of the bumper A.

N is the coupling-link, which is made similar to the ordinary link, except that its ends project, as shown in figs. 1 and 2, to more certainly operate the sliding plate D, and also to hold the link in a horizontal position, ready to enter the bumper of the adjacent car, when the cars are run together.

The head of the pin B is made broad, so as to cover the upper ends of the two tubes, C and H, so that when the spring I is released by the drawing back of the catches J, the elasticity of the spring I may throw the coupling-pin B out of place and uncouple the cars.

By this construction, should one or more of the cars be thrown from the track, the link N will be forced against one of the levers K, and thus withdraw the catches J, uncoupling the cars automatically, and preventing the other cars from being dragged from the track. The levers K may be held forward by coiled or equivalent springs placed behind them, to prevent

the said levers and the catches operated by them from being jarred out of place.

Having thus described my invention,
I claim as new, and desire to secure by Letters Patent—

1. The combination of the slide G with the sliding plate D E F, coupling-pin B, and bumper-head A, substantially as herein shown and described, and for the purpose set forth.

2. The spring I, catches J, levers K K', connecting-

bars L, and equal-armed lever M, in combination with the bumper-head A and coupling-pin B, substantially as herein shown and described and for the purpose set forth.

The above specification of my invention signed by me this 16th day of December, 1869.

SAML. J. ANDERSON.
